UNITED STATES PATENT OFFICE.

JACOB J. PLUCKER, OF PHILADELPHIA, PENNSYLVANIA, ASSIGNOR, BY MESNE ASSIGNMENTS, TO JAMES S. JOHNSON, OF PHILADELPHIA, PENNSYLVANIA.

FIREPROOF CASING FOR ELEVATOR-SHAFTS.

SPECIFICATION forming part of Letters Patent No. 734,602, dated July 28, 1903.

Application filed December 5, 1902. Serial No. 134,034. (No model.)

To all whom it may concern:

Be it known that I, JACOB J. PLUCKER, a citizen of the United States of America, and a resident of 6820 Paschall avenue, Philadelphia, Pennsylvania, have invented certain new and useful Improvements in Fireproof Casings for Elevator-Shafts, of which the following is a specification.

My invention relates to improvements in fireproof casings for elevator-shafts, and has for its object to provide a grillework construction which may be normally opened for the admission of light and air to the shaft and which may also be closed to cut off communication between the building and the shaft in case of fire.

In referring to the drawings, wherein like reference-numerals are used to designate corresponding parts wherever they occur, Figure 1 is a front elevation of a section of grille-work-casing embodying my invention. Fig. 2 is a sectional view showing the grillework closed. Fig. 3 is a view similar to Fig. 2, showing the grillework open.

My improved casing consists of two series of plates 1 and 2, of iron or other suitable fireproof material, said plates being placed one directly back of the other. These plates are of exactly the same design and have open grillework-sections 3 and closed sections 4, the closed sections being of the same width as the open sections. The outer of these two series of plates is preferably secured to the elevator-shaft casing, and the inner plate is adapted to be moved by any suitable mechanism, so that the open and closed sections of each plate may be brought opposite each other in each case, which will be the normal position of the plates, and the shaft will be opened for light and ventilation; but in case of fire the movable plate

may be moved in relation to the stationary plate so that the closed section of one plate will be opposite the open section of the other plate, and vice versa, whereby the elevator-shaft will be entirely closed and cut off from communication with the rest of the building. Any suitable mechanism may be employed for operating these plates; but as this mechanism forms no part of the invention disclosed in this application I have not illustrated such a mechanism.

Having thus described my invention, what I claim as new, and desire to secure by Letters Patent, is—

1. A grillework for elevator-shafts composed of two series of plates provided with sections of open grillework and closed sections, said plates being so constructed in relation to each other that they may be moved so as to bring the open parts of each section in register to admit light and air to the shaft, or may be moved so that the open parts will be out of register, and the shaft closed.

2. A grillework for elevator-shafts composed of two series of plates one located back of the other and surrounding the shaft, said plates being of the same design and provided with alternate sections of open and closed work, one series of plates being permanently fixed in position and the other series of plates being movable, whereby when the plates are in one position light and air may be admitted to the shaft and when they are moved to the other position all communication with the shaft is cut off.

Signed by me at Baltimore, Maryland, this 22d day of October, 1902.

JACOB J. PLUCKER.
